STAPLING MACHINE

Clarence C. Stuewe, Cleveland, Ohio

Application August 23, 1945, Serial No. 612,172

6 Claims. (Cl. 1—49)

1

This invention relates to improvements in stapling machines and more particularly to improvements for supports for stapling machines such as is described in the patent of Joseph A. Forgey, No. 2,360,484, of October 17, 1944.

As is well known to those versed in the art, it has become the practice to provide stapling machines which may be used for driving staples through the barrel hoops and staves into the barrel head. More commonly, such machines are used to drive staples which secure the head into the barrel and also to hold a cleat in its proper place on the end of the barrel. In this respect, after the barrel head is placed in position, with the edge of the barrel head extending into grooves in the staves, a steel or wooden hoop is placed around the staves at the chime of the barrel, and the staples are then driven through the hoop and the staves into the head of the barrel. This may be effected by the use of a machine as disclosed in the aforesaid patent.

The machine for driving the staples is provided with a supporting member in the nature of a foot, which is sometimes called a segment, that rests on top of the barrel and the staple driving mechanism is supported by the segment in its proper position where it overhangs the edge of the barrel in such a manner that when the mechanism is operated the staple is forced by the mechanism through the hoop and the barrel staves into the head.

One of the problems in such mechanisms is to provide proper alignment of the stapling machine with the head so that the staple will go into the head at the edge thereof without being so close to the upper or lower surface of the head that it would split the material and thus weaken the hold of the staple. The problem is made more difficult because the barrel heads are not all of the same thickness. It has been found therefore that the staple entered the head either nearer to the top or nearer to the bottom, depending upon the thickness of the head. This made it necessary to design a number of different segments for the specific type of head being secured and for the workman to select a particular segment for stapling a particular head.

By the present invention, I have made an improvement in a segment or foot which enables the one segment to be used to drive stakes into either metal or wooden cleats. To this end my invention contemplates provision of the segment which is adjustable so that the stapling head of the machine may be placed at any point for stapling and the staples thus properly aligned

2

to enter the head in its mid portion. Furthermore, with the present invention, it is possible to use it regardless of the size of cleats normally used, and because of the construction of the segment lends more stability to the device enabling the driving of the staples to be better controlled.

In connection with the use of wooden cleats, it will be appreciated that it is often desirable to drive the staple through the hoop and stave into the end of the cleat which is above the head. In this respect, the device of my invention adapts itself readily to such procedure which previously could not be effected by the prior art devices, that is, a stapling machine adapted for driving the staples into the head could not drive, without auxiliary apparatus, staples into a wooden cleat.

Although I have stated that the invention is used for stapling barrels, it will be apparent that it can also be used for stapling barrels, kegs, drums, and other containers.

Other aspects of the invention and the invention itself will become more apparent from the following description of an embodiment thereof, which description is illustrated by the accompanying drawings and forms a part of this specification.

In the drawings:

Fig. 1 is a fragmentary side view of a stapling machine disposed on top of a barrel with portions of the machine and barrel broken away to show the manner of its cooperation with barrel head;

Fig. 1A is a plan view partly in section of the device of Fig. 1 taken on the line 1A—1A of Fig. 1;

Fig. 2 is a front elevational view of the device removed from the stapling machine;

Fig. 3 is a side view thereof;

Fig. 4 is a plan view of the device with the stapling machine removed and illustrating the position taken during the stapling of the staves to the barrel head; and

Fig. 5 is a similar view showing the position taken by the device when stapling the staves to a cleat.

Referring now to the drawings throughout which like parts have been designated by like reference characters, as best shown in Fig. 1, the apparatus comprises a stapling head 1 which carries a magazine 2 for the staples and is provided with the arm 4 which assists in supporting the machine in its upright position by engaging with the top of the barrel chime. The stapling mechanism is operated by a hand lever 5 connected at 6 to the staple driving mechanism. The staple

driving mechanism can be of any well known type, one such mechanism being clearly shown and described in the patent to Robert F. Stepbach, No. 2,303,509.

As previously stated, the arm 4 assists in holding the machine in its upright and properly aligned position. The bulk of the weight of the machine is supported by the segment which may rest directly on the barrel head and holds the machine in its proper position. As shown in Fig. 1, the head includes a pair of side plates 7 between which the staple driving mechanism is carried and which extend rearward over the barrel chime and are connected to the support 4. These plates extend downwardly as indicated at 10 '1 in spaced parallel relation to define a channel therebetween.

The segment or supporting foot, which is secured to the member 7, comprises a body 8 of substantially rectangular formation and appreciable thickness as best shown in Figs. 2 and 3. The upper face of the body is provided with a pair of transverse channels 9 into which the portions 10 of the side plates may extend.

Intermediate the channels there is provided an upstanding boss 10, which is adapted to extend upward between the plates 1' as best shown in Fig. 1. The boss 10 is provided with a threaded aperture 11 adapted to receive a screw 12, the head 13 of which engages with the cross bar 14 that rests on top of the members 7 of the stapling head and which when tightened causes the segment to be securely held to the body of the stapling machine.

The opposite ends of the segment are machined to provide each end with vertical ways 15 adapted to receive a tongue 16 of an adjustable shoe member 17; these ways may be dovetail shaped if desired. As best shown in Figs. 2 and 3, the members 17 may be substantially twice the height of the member 8. Each of these members is provided with a vertically extending slot 18 through which a headed screw 19 extends and is threaded into the member body. This screw may be a shoulder screw so that the member may be secured in place and still remain free to move upward and downward. It will be thus seen that these members are capable of vertical movement on the ends of the segment. This movement is such that the lower ends 20 of the members may be raised until they are flush with the bottom side 8' of the segment or lowered to a position as shown by the dotted lines in Fig. 2 where they extend considerably below the bottom of the main body of the segment. The screws 19 may be cap screws or screws having wings thereon if desired. It will also be noted that these members 17, as best shown in Fig. 4, may be wider than the segment body, and that the vertical edge thereof is curved as indicated at 21. The curvature of this edge may be varied but is preferably of the same radius as the radius of the inside of the standard barrel head or chime. It is also provided with a lip 22 which provides a sharp edge for engagement with the chime of the barrel. If desired, there may be occasions where it is desired to clamp the feet in a predetermined position. In this event, the screws 19 would be tightened to effect such clamping action.

The intermediate portion of the body 8 is provided at the base thereof with a forwardly projecting curved portion or lip 22, best illustrated in Figs. 2 and 4, the edge of which slants backward and upward toward the body. The

curvature of the lip 22 may be of substantially the same radius as that of the barrel chime. One design of segment may be suitable for stapling several sizes of barrels.

In operation, as shown in Fig. 1, the stapling machine rests on the end of the barrel with the segment in engagement with the barrel head, supporting most of the weight of the stapling machine and with the staple driving head overhanging the side of the barrel. The arm 4 extends over and may rest on the opposite edge or the rim of the barrel. In case the machine is not on a cleat, as when the staples are being driven into the head (Figs. 2, 3 and 4), the shoes 17 move upward to the position shown in full lines in Fig. 2 with the curved faces 21 of the feet and the lip 22 in engagement with the chime or the inner edges of the staves.

If it is desired to staple the cleat, the stapling machine is placed with the segment on top of the cleat (Fig. 5), in which event the parts 17 drop downward to the position shown by the dotted lines in Fig. 2, with the bottom of the feet resting on the head of the barrel and with the forward curved edges at the bottom engaging the chime. This enables the segment to bridge the cleat on the barrel head and hold the stapling head in the proper position for driving the staple through the chime into the cleat. It can be seen that the members 14 automatically adjust themselves as to height of the cleat and that the curved parts engage the chime of the barrel, while further stabilization is realized by the engagement of the face 8' of the segment body with the cleat. In this case, the pressure during the stapling operation is from the members 17 to the inside of the barrel chime.

The curved surface being in engagement with the staves on the inside of the chime provides a means for holding the head and staves against further movement when the stapling mechanism is operated. The width of the segment affords lateral stability to the device when supported on the head thus assuring that the machine will not tilt and drive the staples in crooked. It should be borne in mind, however, that the length of the segment as disclosed in the drawings is merely exemplary of a preferred form of the invention and that it could be increased in length should it be desired or even shortened if the general run of barrels are of the smaller size. The curvature will be determined by the size of barrel being stapled.

Having thus described my invention, I am aware that numerous and extensive departures may be made therefrom without departing from the spirit or scope of the invention.

I claim:

1. In a stapling machine having a stapling head adapted to drive staples extending to one side of a barrel and provided with a pair of spaced parallel side walls extending over the barrel head, a shoe for supporting said machine from said barrel head comprising a body member having grooves 60 for receiving said side walls, fastening means extending into said shoe body and between said side walls, said shoe having portions extending laterally from said side walls, the ends of said shoe being provided with feet, said shoe and feet being provided with interlocking tongues and grooves and screw means extending through said feet into said body for adjustably holding said feet to said body.

2. A shoe for a stapling machine for holding the stapling machine in a predetermined position

for stapling a barrel, comprising a body portion formed with a vertical way in each end, a pair of members for said ends each formed with a tongue extending into said way, an elongated vertical opening in each of said members and screw means extending through said openings and threaded into said body portion adapted for holding said members in predetermined position on said body, said members adapted to rest on the barrel head and formed to engage the chime of the barrel to hold said stapling machine against movement during a stapling operation.

3. In combination with a stapling machine having a stapling head for driving staples through barrel hoops and staves into the heads and cleats of barrels, said stapling head adapted to hang over and below the chime on the outside of the barrel, means on said head extending over the barrel head including a shoe carried by said head spaced from the overhanging portion and comprising a body member said shoe having portions extending laterally from said stapling head, feet carried on the ends of said shoe adapted to engage the chime of a barrel, said feet being formed with vertically extending slots therethrough and said feet and shoe head being provided with interlocking vertically extending tongues and grooves, and screw means extending through said slots into said shoe for holding the feet in self adjusting position on said shoe.

4. In a stapling machine having a staple driving head, means for supporting said head including a member connected thereto and adapted to rest on the head or cleat of a barrel, said member having a curved lip for engagement with the barrel chime and having portions extending laterally therefrom, movable members loosely carried in the ends of said laterally extending portions adapted for engagement with the chime of the barrel.

5. In combination with a stapling machine having a stapling head adapted to overhang the edge of a barrel head and to drive staples through

the staves into the barrel head, means to support said head in its proper position relative to the barrel head comprising, a member connected to the head and having a body disposed for engagement with the barrel head, said body having portions extending laterally of the stapling head, and movable members disposed on the ends thereof, said movable members having a chime engaging surface, said body being provided with a chime engaging lip intermediate said movable members.

6. In combination with a stapling machine having a stapling head for driving staples through barrel hoops and staves into the heads and cleats of barrels, said stapling head adapted to hang over and below the chime on the outside of the barrel, means on said head extending over the barrel head, a shoe carried by said head spaced from the overhanging portion and comprising a body member, said shoe having portions extending laterally from said stapling head, feet for the ends of said shoe adapted to support said shoe at various heights above the barrel head, said feet having vertically extending slots therethrough and said feet and shoe head being provided with interlocking vertically extending tongues and grooves, and screw clamping means extending through said slots into said shoe for clamping the feet in adjusting position on said shoe, said feet being longer than the thickness of said shoe and movable to positions flush with the bottom portion of the shoe and to alternate positions well below the bottom of the shoe.
